UNITED STATES PATENT OFFICE.

ARTHUR H. WEBBER, OF BOSTON, MASSACHUSETTS.

INTERNAL-COMBUSTION ENGINE.

978,969.

Specification of Letters Patent. Patented Dec. 20, 1910.

Application filed August 6, 1909. Serial No. 511,587.

To all whom it may concern:

Be it known that I, ARTHUR H. WEBBER, a citizen of the United States, residing at Boston, in the county of Suffolk and State of Massachusetts, have invented new and useful Improvements in Internal-Combustion Engines, of which the following is a specification.

This invention relates to internal combustion engines and it has particular reference to engines of the types known as "two-cycle" and "four-cycle." Engines of this character as ordinarily constructed have been operating at a disadvantage for the reason that a portion of the gases generated by each explosion would assemble in the space adjacent to the spark plug, and would be only imperfectly displaced from said space by the fresh explosive mixture entering the cylinder prior to each explosion, the result being that the spark plug would frequently fail to ignite the explosive mixture owing to the presence of an intermediate layer of non-combustible gases and products of combustion.

The present invention has for its object to provide an improved construction whereby, immediately subsequent to each explosion, fresh explosive mixture shall be supplied to the space immediately adjacent to the spark plug from which the non-combustible gases will thus be driven, thereby insuring certainty of ignition and avoiding the loss of power resulting from missing of the ignition of the explosive mixture.

Further ends of the invention are to simplify and improve the general construction and operation of the parts comprising the invention.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention; it being however understood that no limitation is necessarily made to the precise structural details therein exhibited, but that changes, alterations and modifications within the scope of the invention may be resorted to when desired.

In said drawing the single figure repre-

sents a sectional elevation of a portion of a cylinder of an internal combustion engine constructed in accordance with the invention.

The cylinder 5 which is constructed with the customary cooling chambers 6 is provided with a threaded aperture 7 wherein is seated the spark plug B which in the present instance comprises a specially constructed casing 8 having a chamber 9 with which a laterally extending nipple 10 is suitably connected; said nipple being equipped with a check valve 11 shown in the present instance as consisting of a ball valve opening in the direction of the chamber 9. A tubular passage C connects the nipple 10 with the transfer passage 12 through which the explosive mixture is introduced into the upper end of the cylinder. For convenience of attaching the tube C, a nipple 14 may be threaded into the cylinder to connect with the passage 12; and the tube C may be provided with terminal flanges 15 secured in the nipples 10 and 14 by means of bushings 16. It will however be understood that the detailed construction may be considerably varied without departing from the spirit of the invention or from the scope of the claim.

When the piston D on its downward stroke allows the pressure in the cylinder to fall below that in the base or crank case, a small quantity of pure explosive mixture is forced from the passage 12 through the tube C and into the chamber 9 where it displaces the burned gases, leaving the chamber or pocket filled with an absolutely pure mixture which will not become adulterated with any products of combustion left in the cylinder. The ball check 11 prevents the mixture being forced back through the tube C during the compression stroke. Each compression stroke finds the points of the spark plug surrounded by a layer of pure explosive mixture which is very easily ignited and which in turn will fire a very poor mixture in the firing chamber 9.

In the two-cycle engine as heretofore constructed it has been found impossible to throttle the engine to any extent without its missing or skipping badly owing to the large quantity of burned gases left in the cylinder subsequent to each explosion being mixed with a relatively small charge of incoming explosive mixture, and the heat of the spark being insufficient to fire the mixture thus adulterated under ordinary conditions.

Practically the same difficulty applies to engines of the four-cycle type.

The present invention not only eliminates the missing or skipping and the loss of power consequently upon, but it allows the engine to be successfully operated with a poor or leaner mixture, thus effecting a considerable saving in fuel.

It is obvious that the more the engine is throttled, the more mixture in proportion to the entire charge will pass through the tube C and into the chamber 9, thus rendering the action of the device positive under all conditions of throttling. In a four-cycle engine, the intake end of the tube C may be connected with the intake pipe or manifold.

Instead of the special spark plug herein shown, the device may be constructed of an ordinary spark plug combined with a special fitting; or the pocket or chamber to receive the charge adjacent to the spark plug may be formed in the wall of the cylinder. These and other modifications obviously come

within the range of mechanical skill and do not require to be illustrated in detail.

Having thus described the invention, what is claimed is—

In an internal combustion engine, a cylinder having a transfer passage, a spark plug threaded into the end of the cylinder and having a pocket formed adjacent thereto, a nipple threaded into the spark plug and having a valved passage, a nipple threaded into the cylinder and opening into the transfer passage through which explosive mixture is introduced into the upper end of the cylinder, and a tube connecting the two nipples to convey a portion of each explosive charge to the direct vicinity of the spark plug.

In testimony whereof I affix my signature in presence of two witnesses.

ARTHUR H. WEBBER.
